CRATE FASTENER

Oscar Sliger, St. Louis, Mo., assignor to The Mengel Company, Louisville, Ky., a corporation of New Jersey

Application December 20, 1934, Serial No. 758,506

6 Claims. (Cl. 217—22)

This invention pertains to bottle crates, and more particularly to an improved means for securing the partitions thereof to each other.

Bottle crates are, as is well known, subject to rough treatment, both during commercial handling and filling, as well as by the careless usage in some homes.

The main object of the present invention is to provide an anchoring and securing means for the partition elements of the crate, the structure being simple in form and construction and ready for placement with reference to the various partitions.

A further object is to provide a securing device which when secured to one series of the partitions, will present means which acts to guide and to properly position the other series in place as the elements are assembled, and to maintain them in such relationship, this irrespective of any interlocking or inter-engagement of the partition elements, as by a gained or notched construction.

The invention is illustrated in the annexed drawing, wherein:—

Figure 1 is a perspective view of a crate with one of the partitions broken away to more fully disclose the structures which fall within the scope of the invention;

Fig. 2, a perspective view, on an enlarged scale showing sections of several partitions in different relative positions and, likewise, several of the partition positioning and securing means;

Fig. 3, a plan view of the flat cut or stamped out blank from which the securing means is produced; and

Fig. 4, a perspective view of one of the securing members, as seen looking toward its lower face, with the component elements thereof brought to that position which they assume when interlocked with the partition structure.

In the drawing, the body of the crate is shown as of the usual commercial form, that is as oblong, the sides being denoted by 10 and 11, the ends by 12 and 13, and the bottom by 14, these elements being secured together in any approved manner, as by nailing and the employment of binding straps 15 and 16.

The longitudinally extending partitions are denoted by 17 and the cross ones by 18. They may be formed from any suitable material, such as thin lumber, plywood, etc.

Preferably, the longitudinals are of a depth somewhat less than that of the transverse ones and will have formed in their lower edges or portions, slots as 19 from which and in line there-

with extend upwardly and oppositely disposed gains as 20 and 21. While such gains are preferable, with a view of interlocking the various partitions, their presence is not necessary, as will presently appear.

The cross partitions 18 are slotted or notched out from their upper edges downwardly, which slots are designated by 22 and 22^a, respectively. The first slot will be somewhat narrower so that the side edges of the wall which form the slot, 10 will enter the gains 20 and 21 and interlock the partitions 17 and 18.

The slot 22^a, however, is of a width equal to the thickness of the transverse partition with which it is designed to cooperate, inasmuch as when the parts are assembled, the side walls of this slot 22^a will contact the side faces of the longitudinal. With a view of stabilizing the structure, it is preferred to use the notched and gained arrangement best shown in the lower left-hand side of Fig. 2. 20

The securing and anchoring device for the partitions, to hold them against displacement in any direction, one of which is designed to be positioned and secured at the upper edges of the partitions where they cross throughout the series, is 25 formed as above noted, from a single piece of metal. It will be stamped or died out to take the shape shown in Fig. 3, after which it will preferably be partially bent to form, or to that shape shown in Fig. 2, ready for application. It may 30

be said to comprise a main body portion as 24 which, when the fastening is fully positioned, will assume the shape of an inverted U-channel, to conform with the upper edge of the partitions, or to the form according to the contour of said 35 edges. Extending from the lower edge of the channel or body and at each side as an integral part of the body are what may be termed side bearing elements or cheeks 25, 25^a and 26, 26^a, said elements standing opposite each other in 40 pairs, and each at its lower end having a spur as 27 formed thereon.

As will be seen upon reference to Fig. 4, each of these spurs extends inwardly at right angles to the cheek of which it forms an extension, and 45 penetrates the partition or separator 17 when the fastener is fully pressed down and the cheeks forced inwardly into contact with the partition.

By cutting the metal blank upon the lines x and y, (Fig. 3), and preferably cutting out a triangular section as x' and y' at the inner end of each of said cuts, a section of the blank is produced which permits the outbending thereof to form a wing extending outwardly at right angles to each of the cheek members heretofore referred to. 55

These members stand in pairs opposite each other and are denoted by 28, 28^a, respectively, on one side, and 29, 29^a, respectively, on the opposite side.

As will be seen upon reference more particularly to Figs. 2 and 4, these wings are arranged in pairs, the wings of each pair standing parallel to each other and at right angles to the main body 24 of the fastener or anchoring element. They are spaced apart a distance sufficient to make close contact with the upper portion of the side faces of the cross partitions 13 when the fastener is forced downwardly and bent to final position.

By reason of the fact that the wings are arranged in pairs in parallel position, the fastener 15 may be secured to the upper edge of a partition and thereafter the other cross partition moved upwardly with reference thereto and guided to its final place between the wings above mentioned. Such a fastener, secured to a partition 20 and adapted to receive the upper end of another partition, is shown at the extreme left-hand side of Fig. 1.

The formation of the fastening device is such 25 that it has a body member carrying the elements adapted to embrace the adjacent side faces of each of the cross partitions or separators, which elements or members stand at right angles to each other and certain of which carry means for bringing about an engagement of the fastener with one 30 or the other of said cross partitions.

Stated in a brief way, the fastening may be said to comprise a main body element adapted to 35 overlie and partially conform to the contour of the partitions with which it is to be associated, together with embracing elements angular in outline and contacting the side faces of each partition adjacent the upper marginal portion thereof.

A further aspect of the structure involves the 40 use of anchoring means such as the spurs 27. It is conceivable, however, that the latter may be omitted and the cheeks and wings pressed inwardly to such an extent as to definitely hold the fastener in place through frictional engagement and slight indentation of the material of which 45 the separators or partitions are formed.

Under either construction, the right angle relation existing between the cheeks and wings ensures a close fit and binding action of said elements with the partitions at their point of crossing, preventing any displacement short of breakage. The close fit just mentioned is also, in a 50 measure, brought about by tapering the outermost edge of the prong and inclining it inwardly toward its point. This ensures a drawing action which assists in forcing the wings against the cross partition.

Should a partition become broken, the anchoring means associated therewith may be removed 55 without difficulty and a new partition substituted and the parts re-anchored; thus, the crate does not have to be disposed of merely because one partition is broken.

By making the cut-outs in the blank as x' and y', the upper edge of each cheek will, when the 60 fastener is secured in place, lie below the upper

edge of the partition with which it cooperates, thus precluding its catching upon anything, with a consequent breakage or possible displacement.

What is claimed is:

1. An anchoring element for cross partitions of 5 crate-like structures, comprising an inverted channel-shaped body portion; cheeks arranged in pairs at the sides of and adjacent each end of said portion; and a wing extending outwardly from the inner portion of each cheek at right angles thereto and as a continuation thereof.

2. An anchoring element for crossed partitions of 10 crate-like structures, comprising an inverted channel-shaped body adapted to overlie the upper edge of one of said partitions; and a member 15 extending downwardly from the body at the ends of the side portions thereof, said members each being substantially right angular in cross section, the apexes of the angles, when the anchoring element is positioned on the partitions, extending into the angles formed by the partitions 20 at their lines of crossing and said members contacting the various faces of the partitions at and adjacent said lines.

3. A structure as set forth in claim 2, wherein 25 an element of each of said L-shaped members is formed at its lower end with an inwardly extending prong.

4. A structure as set forth in claim 2, wherein 30 an element of each of said L-shaped members is formed at its lower end with an inwardly extending prong, the outermost edge whereof is inclined inwardly toward its point.

5. An anchoring device for cross partitions of 35 a crate-like structure, said device being produced from a single piece of sheet metal bent to form and comprising a body element, said body element having associated therewith four downwardly extending members each right angular in transverse cross section, each of said members, 40 when the body element is positioned with reference to the partitions at their zone or point of crossing, bearing directly against the sides of the partitions with its apex entering into the immediately adjacent reentrant angle formed by 45 the partitions.

6. An anchoring device for cross partitions of 50 a crate like structure, said device being produced from a single piece of sheet metal bent to form and comprising a body element, said body element having associated therewith four downwardly extending members each right angular in transverse cross section, the adjacent elements of each of said members standing in parallel relation to each other with the upper edge of those elements which extend outwardly at right angles to the body element lying in a plane below that of the upper portion of said body element, and each of said members, when the body element is positioned with reference to the partitions at 55 their zone or point of crossing, bearing directly against the sides of the partitions with the apex of its angle entering into the immediately adjacent reentrant angle formed by the partitions.

OSCAR SLIGER.
